UNITED STATES PATENT OFFICE

2,633,547

TWO-SIDED ELECTRON-SENSITIVE SCREEN

Harold B. Law, Princeton, N. J., assignor to Radio Corporation of America, a corporation of Delaware

Application June 30, 1950, Serial No. 171,394

5 Claims. (Cl. 313—92)

1

This invention relates to cathode-ray tubes and particularly to improvements in "two-sided" electron-sensitive screens or targets for such tubes.

It has previously been proposed to derive signals from the rear surface of a cathode-ray screen and to utilize said signals for controlling the focus or the timing of the beam, or for securing linear, vertical, radial or other directional scanning movements of a high order of precision. By way of example, Zworykin in U. S. Patent 2,415,059 shows a color-kinescope having a screen made up of a multiplicity of groups-of-three phosphor coated lines, each capable of emitting light of a different color, and three photocells, at the rear of the screen, each sensitive to one of the colors emitted by the color-phosphor lines. The control signals generated by the photocells are employed to accelerate or decelerate the deflection of the beam in accordance with its departure from the phosphor-line being scanned. The control signals thus serve to restore the instantaneous line-deflection path of the scanning beam on that phosphor line. Obviously, the amplitude of the control signals in Zworykin's color-kinescope is a function of the intensity of the lights which the photocells pick up from the rear of its screen. It will therefore be apparent that when any portion of the televised scene contains a relatively dark area, only very weak photo-electric signals are available for control purposes.

Accordingly, the principal object of the present invention is to provide an improved "two-sided" electron-sensitive screen of the general character described, and one characterized by the increased intensity of the light, available for control purposes, adjacent to its rear surface.

Another and important object of the present invention is to achieve said principal object without any substantial diminution in the intensity of the fluorescent light emanating from the obverse face of said screen, or any increase in the length and width dimensions of the screen.

Still another object of the present invention is to provide an improved color-image tube of the kind wherein the beam is subjected to vernier-control signals derived from the rear surface of its screen, and one wherein said control signals are derived from a "fast" phosphor whose color is unimportant from the standpoint of image rendition.

Stated generally, the foregoing objects are achieved in accordance with the invention by the provision of an electron-sensitive target comprising an electron-transparent light-reflecting layer

2

having any desired pattern of color-phosphor materials on its obverse face and a discrete electron-transparent signal emissive phosphor material of the desired color-emissive and light-decay characteristics on its opposite or rear surface. The light emitted by impact of the electron-beam is reflected rearwardly by the light-reflecting layer and is picked-up, as by a photocell, and the resulting signals used, as before, to control the focus or timing of the beam. Since the light emitted by said signal-generating phosphor layer is reflected rearwardly, and is not visible from the front of the tube, it may have color and decay characteristics other than that of the phosphor or phosphors on the obverse face of the screen. When the tube in which the screen is contained is of the color-kinescope variety the velocity of the beam varies with the light and shade of the scene being televised. Thus if a bright area is to appear on the screen the intensity of the beam is quite high so that it passes through the electron-transparent signal-generating and light-reflecting areas and activates the picture-generating phosphor or phosphors on the obverse surface of the light reflecting layer. On the other hand if a dark picture-area is indicated (by the video signal) the intensity of the beam is made sufficient merely to actuate the signal-generating phosphor indicia on the rear of the screen. Thus, contrary to the usual practice, control signals are available irrespective of the instantaneous-degree of light and shade of the televised image.

The invention is described in greater detail in connection with the accompanying single sheet of drawings, wherein,

Fig. 1 is a partly diagrammatic view of a television receiving system employing a color-kinescope having a two-sided screen constructed in accordance with the principle of the present invention and,

Fig. 2 is a partial sectional view of the screen of Fig. 1.

In the drawing the invention is shown applied to cathode-ray tube of the color-kinescope variety. The tube here shown is of conventional shape and dimensions and comprises an evacuated glass envelope having a main chamber in the form of a frustum 1, which contains the electron-sensitive screen 3 (later described) and a neck portion 5 containing the cathode 7, grid 9 and first anode 11 of an electron gun.

The frustum of the envelope contains a hermetically sealed port or lens 13 through which light, emanating from the rear surface of the

screen 3, passes to a photocell 15 on the outside of the envelope. As is conventional, the envelope also contains an accelerating electrode or second anode in the form of a conductive coating 17 on the inner surface of the main chamber 1 and neck 5. As is also conventional, horizontal and vertical magnetic deflecting coils 19 and 21 are provided on the neck of the tube for imparting the requisite screen-scanning movements to the electron beam (not shown).

In the embodiment of the invention which has been selected for illustration the target or screen 3 comprises a glass or other transparent foundation 23, which is provided on its rear face with a multiplicity of groups-of-three phosphor lines R, B and G extending in a direction perpendicular to the direction of line scanning. Each line is constituted of a phosphor material capable of emitting light of a particular color component when struck by the beam emanating from the gun of the tube.

As taught by Leverenz in U. S. Patent 2,310,863 when the phosphor lines which make up the different groups are to emit blue, green and red light, respectively, the materials of which the lines are composed may comprise: Silver-activated zinc sulfide and zirconium silicate for the blue lines B. Alpha-willemite activated with manganese or zinc cadmium sulfide activated with silver for the green lines G. Chromium-activated aluminum beryllate or zinc cadmium sulfide activated by silver for the red lines R.

The phosphor layers R, B, and G, here illustrated, extend in unbroken lines from the bottom to the top of the transparent foundation plate 23. They may however be made up of a multiplicity of phosphor dots of sub-elemental image dimensions and, in either event, may extend horizontally across the screen, if desired. They may be applied to the foundation 23 in any convenient manner, e. g. by means of a "silk-screen" (not shown), a spray-gun and mask (not shown) or by a conventional "settling" process, from a liquid suspension of phosphor particles.

After the three color-phosphors R, B, and G have all been laid down on the foundation 23, an electron-transparent light-reflecting layer 25, preferably of aluminum, is laid down on top of the phosphor lines or dots as by a conventional evaporation process, in vacuo. Thereafter the 50 electron-transparent signal-generating lines 27 or other indicia are laid down, as through a mask, not shown, on top of the light-reflecting layer 25 in register with the underlying picture-generating phosphor areas. In the instant case but one signal-generating line 27 is used for each group-of-three picture-generating lines R, B, G. These extremely thin signal-generating lines 27 are preferably constituted of zinc oxide or other "fast" phosphor, i. e. one having a rapid light decay-characteristic. The color of the light emitted by the signal-generating phosphor 27 is immaterial where but one signal-generating line or area is used for each group-of-three picture-generating phosphor areas.

If more than one signal generating phosphor is employed they should exhibit different color-emissive characteristics. In such an embodiment of the invention, separate photocells (not shown) are employed to pick-up the different color-signals, as in the Zworykin patent.

When the concentration of the phosphor particles which make up the picture-generating lines R, B and G is the same, green phosphor will ordinarily emit light of an intensity greater

than that of the colored lights emitted by the blue and red phosphors. Hence when the signal-generating phosphor layer 27 is placed in register with the green phosphor G no serious or even noticeable attenuation in the colored image results from the passage of the beam through the electron-transparent layers 25 and 27.

The circuit shown in Fig. 1 for utilizing the signals generated by the impress of light from the rear of the screen 3 upon the light-sensitive device 15 forms no part of the present invention and in fact is a duplicate of the circuit claimed by Paul K. Weimer in copending application Serial No. 5,431, filed January 30, 1948, now Patent No. 2,545,325. Here the output of the photocell or other suitable light-sensitive device 15 is applied to a signal clipper 29 which takes out variations in the intensity of the light resulting from the variations in the video signals, which are applied to the grid 9 of the tube. The pulses of constant amplitude, derived from the signal clipper 29 are applied to a pulse delay line 31 which operates, in timed sequence, through amplifiers 33, 35 and 37 to trigger on switches 34, 36, 38 which pass the "green," "blue" and "red" video-signals, to the grid 9 of the tube.

In conclusion it should be noted that the synchronizing signal maintains its control so long as there is light output from the signal-generating zinc oxide coatings 27. Thus, control is maintained even when the picture-generating phosphor areas G are down to "black" level due to the attenuation of the beam in the zinc oxide and aluminum layers.

What is claimed is:

1. An electron-sensitive color target comprising a foundation having a multiplicity of groups of phosphor-coated elemental areas on a surface thereof, said elemental areas each being constituted essentially of a phosphor material capable of emitting light of a color individual to that area, an electron-transparent light-reflecting metal layer supported upon said groups of phosphor coated areas, and a plurality of discrete electron-transparent phosphor coatings disposed on said metal layer each in register with a particular one of the elemental color-phosphor areas of each group.

2. The invention as set forth in claim 1 and wherein each of said electron-transparent phosphor coatings comprises a phosphor material capable of emitting light of a color corresponding to that of the light emitted by the phosphor coated area with which said transparent-coating is in register.

3. The invention as set forth in claim 1 and wherein the phosphor material of which one of said elemental areas is comprised is of a type that normally emits colored light of an intensity greater than that of the intensity of the colored lights emitted by the phosphor materials of the other elemental areas, and wherein said electron-transparent phosphor coatings are disposed in register with the elemental areas of said greater light intensity characteristic.

4. The invention as set forth in claim 1 and wherein said discrete electron-transparent phosphor coatings are constituted essentially of a phosphor material having a light-decay characteristic which is rapid as compared to the light-decay characteristics of the phosphor materials of which said phosphor-coated elemental areas are comprised.

5. The invention as set forth in claim 4 and

wherein said discrete electron-transparent phosphor coatings are constituted essentially of zinc oxide.
